UNITED STATES PATENT OFFICE.

WILLIAM J. FINNEN, OF SHARON, PENNSYLVANIA, ASSIGNOR TO WESTINGHOUSE ELECTRIC & MANUFACTURING COMPANY, A CORPORATION OF PENNSYLVANIA.

TRANSFORMER.

Application filed March 31, 1926. Serial No. 98,669.

My invention relates to electrical translating devices and particularly to bracing devices for electrical transformers.

One object of my invention is to provide 5 an electrical transformer, the tank walls of which shall not be required to brace the coils and core members of the transformer.

Another object of my invention is to provide an electrical transformer in which an 10 auxiliary bracing structure prevents the coils and core members from coming in contact with the transformer wall during movement or shipment of the transformer.

A further object of my invention is to provide 15 an electrical transformer, the walls of which may be of relatively light material by reason of the fact that they are relieved from all shocks and stresses that may arise from movement of the coil and core members of 20 the transformer.

With the steady increase in the size of electrical transformers, the problem of dissipating the heat generated therein has been a serious problem with electrical engineers. 25 Since the rate of heat dissipation is inversely proportional to the thickness of the tank wall, it has become more important that the walls of such transformers be made as thin as possible.

Where the wall of the transformer is only required to support the weight of the insulating oil, it is possible to utilize sheet metal of .078 inches gauge. With such thin tank walls, however, it is necessary that the 35 heavy mass of material constituting the coils and core members shall be secured in place by means other than the transformer walls. During shipment, it frequently happens that the cars on which the transformers are being 40 shipped are subjected to sufficiently severe jolts to cause the core and coil members to strike the tank walls with such force that leaks result. I avoid the foregoing difficulties by constructing a bracing frame within 45 the transformer tank that firmly fixes the core and coil members in place and is not attached to the tank walls.

In the accompanying drawings.

Figure 1 is a broken view, partially in elevation and partially in section, of an electrical transformer embodying my invention.

Fig. 2 is a plan view of the transformer shown in Fig. 1 and;

Fig. 3 is a plan view of a modified form of 55 my invention.

Referring particularly to Figs. 1 and 2 my invention comprises in general an electrical transformer 1 of rectangular cross-section and having the usual side walls 2 of relatively thin metal that are secured as by welding to a base frame 3, a header member 4 that is welded to the upper edges of the side walls 2 thereby forming a liquid tight housing for the transformer core and windings 5 together with a bracing frame 6 that extends between the base 3 and the header member 4.

The base frame 3 and the header member 4 may be of any desired construction. The bracing frame 6 is in the form of a steel 70 frame-work. Within the tank walls 2 and independent therefrom, at each corner of the rectangle there is mounted an angle iron 7 in vertical position. The lower ends of the angle irons 7 are firmly welded or riveted to 75 the base frame 3 and extend upwardly and engage the header member 4 to which they are also welded or riveted, whereby they constitute the corners of a frame for transmitting, supporting and lifting strains between 80 the header member 4 and the base frame 3. The tank walls 2 are only called upon to support and confine the insulating oil surrounding the transformer coils and core members 5.

Cross braces 8 are secured between the angle irons 7 at their lower ends and at points sufficiently high to give rigidity to the several angle irons 7 thereby constituting the bracing frame 6. It is to be understood 90 that the cross braces 8 shown in Fig. 1 are duplicated around the four sides of the transformer. The frame 6 thus constituted is at all points free from physical engagement with the tank walls 2.

The vertical elevation of the cross braces 8 may be the same for a number of sizes of the transformer core and winding members 5, thereby resulting in a material saving in the cost of manufacturing several 100 number of styles and sizes of transformers.

Referring particularly to Fig. 2, the coil and core members 5 may be bodily lowered into the transformer casing between the several angle irons 7, whereby the angle irons act as guides for the core member and prevent it from damaging the walls 2. In order to procure a snug engagement between the angle irons 7 and the core and coil members 5, sections of angle irons 9 are secured to the 110

upper edges of the transformer coils and core member 5 that engage, and fit into the angles of, the angle irons 7.

- 5 If, during shipment, the transformer 1 is subjected to a jar so severe as to cause the coils and core members 5 to move laterally in the tank a sufficient amount to tend to endanger the transformer walls 2, the angle irons 9 engage the vertical angle irons 7.
- 10 The strain thus transmitted to any angle iron 7 is transmitted by the attached cross braces 8 to the base member 3 at the adjacent corners of the transformer and, accordingly, the coil and core members 5 are
- 15 brought to rest by the bracing action of one or more of the angle irons 7 without any blow being delivered to the tank walls 2.

Referring particularly to Fig. 3, I have shown wedge members 10 that may be inserted between the coil and core members 11 and the angle irons 7 where the former are of smaller dimensions than those of the form of my invention shown in Fig. 2. The function of the wedges 10 is similar to that of the angle irons 9 in the other form of my invention.

It will thus be seen that I have devised a bracing structure for transformers in which the shocks that may be produced by movements of the coil and core members are transmitted to a bracing structure that is entirely independent of the transformer tank walls. The transformer walls being thus relieved from the necessity of withstanding severe shocks and jars may be made of relatively thin material as they are only required to support the body of insulating oil, with the result that the rate of heat dissipation of the transformer is much improved over that of transformers having walls of sufficient thickness to serve both as a container and as a bracing structure.

I claim as my invention:

1. In a tank structure, a base member, a frame-work secured thereto, a fluid-immersed device fitting within the frame-work without attachment thereto, and a relatively thin tank wall mounted on the base member surrounding the frame-work without attachment thereto.

2. In a tank structure, a base member, a frame-work secured thereto, a fluid immersed device fitting within the frame-work without attachment thereto, a relatively thin tank wall mounted on the base member sur-

rounding the frame-work without attachment thereto, and a header for the tank wall attached to the frame-work whereby the tank wall is protected by the frame-work from strains incidental to lifting the tank structure and to damage caused by shifting movements of the device within the tank.

3. In a transformer structure, a base member, a frame-work secured thereto, core and winding members fitting within the frame-work without attachment thereto, and a relatively thin tank wall mounted on the base member surrounding the frame-work without attachment thereto.

4. In a transformer structure, a base member, a frame-work secured thereto, core and winding members fitting within the frame-work without attachment thereto, a relatively thin tank wall mounted on the base member surrounding the frame-work without attachment thereto, and a header for the tank wall attached to the frame-work whereby the tank wall is protected by the frame-work from strains incident to lifting the tank structure and to damage caused by shifting movements of the device within the tank.

5. The combination with a liquid-containing casing, of a frame extending longitudinally within said casing, an electrical device within said frame and normally spaced therefrom, and a member connected to said device and projecting toward said frame.

6. The combination with a base member, of a liquid-containing vessel projecting upwardly therefrom, a frame comprising spaced members carried by said base member and extending upwardly within said casing, a header member to which said spaced members are secured, and an electrical device within said frame.

7. The combination with a base member, of a liquid-containing vessel projecting upwardly therefrom, a frame comprising spaced members carried by said base member and extending upwardly within said casing, a header member to which said spaced members are secured, reinforcing members secured to said spaced members, and an electrical device within said frame.

In testimony whereof, I have hereunto subscribed my name this 12th day of March, 1926.

WILLIAM J. FINNEN.
